UNITED STATES PATENT OFFICE.

FREDERICK T. KLING, OF CLEVELAND, OHIO.

CLEANING TUB FOR AUTOMOBILE PARTS OR SIMILAR ARTICLES.

Application filed October 20, 1922. Serial No. 595,737.

To all whom it may concern:

Be it known that I, FREDERICK T. KLING, a citizen of the United States, residing at Cleveland, in the county of Cuyahoga and State of Ohio, have invented certain new and useful Improvements in Cleaning Tubs for Automobile Parts or Similar Articles, of which the following is a specification.

The present invention relates to cleaning tubs specifically adapted for the cleaning of automobile parts or similar articles wherein the tub is so arranged as to receive therein the articles to be cleaned, and wherein means is provided within the tub for saving the cleaning fluid to be again used.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a side elevational view of a device constructed in accordance with the present invention.

Figure 2 is a top plan view thereof.

Figure 3 is a longitudinal sectional view upon the line 3—3 of Figure 2, looking in the direction of the arrows, and

Figure 4 is a vertical transverse cross sectional view upon the line 4—4 of Figure 1.

Referring to the drawings, there is shown a tub embodying side and end walls formed from a single strip of sheet metal 1 bent into the shape of a rectangle, and having its ends suitably secured together by welding, soldering or the like. The upper and lower edges of the strip 1 forming the side walls of the tub are rolled as shown at 2 for effecting beaded ends for the reception of reinforcing wires 3 therethrough. Suitably secured within this strip 1 forming the side and end walls of the container are vertically extending supporting legs 4 at the four corners thereof. Received within the upper open end of the strip 1 forming the side and end walls of the container is a pan-shaped receptacle 5, the outer edges of which are adapted to be rolled upon the upper beaded end of the side and end walls 55 of the container as at 6 for effectively se-

curing the said pan-shaped container therein.

The bottom wall 7 of the pan-shaped container or receptacle 5 is downwardly sloped towards the center thereof, and has formed 60 therein adjacent one of the side walls formed by the strip 1, a fluid receiving well 8, the side walls of which are inwardly sloped for a portion of their length, and the bottom 8' of this well has an opening 65 therein for conducting the cleaning fluid and dirt outwardly thereof through a tube 9 secured to the said bottom wall of the well. The bottom wall 7 of the said pan-shaped container 5 has also formed thereon in transverse alinement with the said fluid well 8, a compartment 10, the bottom wall of which is sloped inwardly towards the well 8 and by reference to Figure 4, it will be noted that the rear wall of this well 70 functions as the forward wall of the said compartment 10, outlet openings 11 being provided in the lower edge of this wall for allowing the fluid to flow from the compartment 10 into the well. The lower end 75 of the above mentioned outlet tube 9 is internally screw threaded for receiving a screw threaded plug 11' and secured to the side walls of the tube formed by the strip of material 1, and vertically projecting centrally thereof, are arms 12, these arms adapted to lie within the opposite ends of the pan-like receptacle 5 for conveniently supporting within this pan, the axle or other elongated member of the automobile 80 to be cleaned. As shown, the upper ends of these supporting legs are suitably dished out for retaining the said axle or other part thereon.

In view of the above description, it will 85 be readily understood that the relatively large articles to be cleaned are supported within the pan-like receptacle 5 at which time, gasoline or other cleaning fluid may be sprayed thereon for cleaning the dirt 90 therefrom, and in view of the inwardly sloping bottom wall 7 of this receptacle, the cleaning fluid will flow within the well 8, and any dirt or sediment off of the parts to be cleaned will also flow within the well 100 to be drained therefrom through the outlet pipe 9 and to be retained for further use, the dirt or sediment having been removed 105 from the cleaning fluid. The smaller articles such as nuts, bolts or the like are to 110

be received within the compartment 10 formed within the pan-like receptacle 5, whereby the same are suitably cleaned therein.

5 While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:—

1. In a cleaning tub for the purposes described, including side and end walls formed of a single length of sheet metal, a pan-like receptacle supported by the upper edges of the side and end walls, and a cleaning fluid well formed within the bottom of this receptacle for the reception and draining of the said cleaning fluid, the bottom wall

of said pan-like receptacle sloping downwardly towards the well for conveying the fluid thereto.

2. In a cleaning tub for the purposes described, including side and end walls formed of a single length of sheet metal, a pan-like receptacle supported by the upper edges of the side and end walls, and a cleaning fluid well formed within the bottom of this receptacle for the reception and draining of the said cleaning fluid, the bottom wall of said pan-like receptacle sloping downwardly towards the well for conveying the fluid thereto, and a pair of supporting brackets within the receptacle for suitably supporting a relatively elongated article within the pan-shaped receptacle.

In testimony whereof I affix my signature.

FREDERICK T. KLING.
